UNITED STATES PATENT OFFICE.

FRANK L. SESSIONS, OF LAKEWOOD, OHIO.

CARBURETER.

1,231,209.

Specification of Letters Patent. Patented June 26, 1917.

Application filed February 4, 1914. Serial No. 816,523.

To all whom it may concern:

Be it known that I, FRANK L. SESSIONS, a citizen of the United States, residing at Lakewood, in the county of Cuyahoga and 5 State of Ohio, have invented certain new and useful Improvements in Carbureters, of which the following is a specification.

Some of the objects of my invention are to provide a carbureter in which fuels may 10 be used which are not readily gasified at normal atmospheric temperatures; and to provide a carbureter in which fuel may be gasified and a proper mixture of air and fuel delivered regardless of the temperature 15 of the surrounding air.

To attain these objects I employ means for heating the fuel and air before and after they are mixed, and a new and improved arrangement of parts which result in 20 marked economy of fuel, and the ready starting of an engine in cold weather.

The construction of my carbureter is such that the heating means may be disconnected, without interfering with the operation of 25 the device, in the manner that ordinary carbureters may be operated when using fuels that are sufficiently volatile to produce an explosive mixture without the use of heating means.

30 Further objects and advantages and the construction of my carbureter will be fully disclosed to one skilled in the art in the accompanying drawings in which,

Figure 1 is a vertical section of a carbureter embodying my invention.

Fig. 2 is a fragmentary section on the same plane as Fig. 1, showing the air inlet valve open.

Fig. 3 is a plan view partially in section 40 on line $a-a$, Fig. 1.

Fig. 4 is a partial section on line $x-x$ of Fig. 3.

Fig. 5 is a sectional view of a modified 45 form of fuel inlet having an adjustable orifice, the section being taken through the axis of the heater pipe, fuel pipe, etc.

Fig. 6 is a plan of the detached air inlet valve.

Fig. 6^a is an elevation of the detached air 50 inlet valve.

Fig. 7 is a diagram of electrical connections to the electric heating coil of my carbureter.

Fig. 8 is a fragmentary section taken 55 through the axis of the heater pipe, fuel pipe and valve lamina 3^a, when the projec-

tions 63 are employed to form a constant opening of said lamina.

Referring to the drawings, 1 is the main body or casing of the carbureter shown in 60 Figs. 1 and 2, preferably made of a metal casting. This part comprises the cylindrical tubular portion 2, open at its lower end forming an air inlet and a passage in which is located the air inlet valve 3; the mixing 65 chamber 4; the cover 5 for the float chamber casting 6; the mixture outlet 7 to the inlet manifold 8 of the engine to which the carbureter is connected; the threaded opening 9 for the heater pipe connection 10; the 70 valve seat 11 for the relief valve 12; the centering support 13 for the heater pipe 14; the air inlet valve stop 15; and the flange 16 for bolting the carbureter to the corresponding flange 17 of the engine intake. 75

18 is a fuel supply and float chamber from which the float valve chamber 19, and needle valve chamber 20 open. 21 is a float which is connected to a lever 22 by means of the slotted post 23 and pin 24. 25 is an 80 adjustable fulcrum post for lever 22. 26 and 27 are similar float valves, each having a circumferential groove 28, on its stem for the reception of one end of the equalizing lever 29. One end of lever 22 is bifurcated 85 so that equalizing lever 29 may stand in the slot 30 so formed. The rising and falling of the float causes both valves to close and open.

31 is a fuel pipe shown as a metal casting 90 comprising the fuel heating chamber or passage 32 which surrounds the heater pipe 14; the hub 33 which is bolted to a corresponding projection 20^a on needle valve chamber 20; and the arm 34 which connects the fuel 95 pipe 31 with hub 33.

35 is a threaded bolt which secures 33 to 34. 35 is drilled axially to form a seat for the needle valve 36 and an outlet for the passage of the fuel from the fuel supply 100 chamber 18 to the heating chamber 32 and drain cock 37. 35 is also drilled transversely and grooved circumferentially at 38 to permit fuel to enter the passage 39 in arm 34 on its way from the needle valve to 105 the fuel heating chamber. I make no claim in this application for the float-valve mechanism herein described and shown in the drawings as it forms the subject matter of my copending divisional application, Serial 110 Number 166,356, filed May 4, 1917.

40 is an electric heating coil which sur-

rounds the fuel pipe 31. 41 and 42 are the wires connecting the coil 40 to the source of current which may be either the storage battery 43, the generator 44, or both. When 5 desired, the coil 40 may be connected to a primary battery. In Fig. 7, I have shown the electrical connections which I prefer to use. In this diagram, the coil 40 is controlled by the switch 45 and the generator 44 is connected to the battery and coil circuits by the switch 46. When starting the engine, the generator 44 may, when properly wound and connected, be used as a motor for cranking purposes. The switches 45 10 and 46 may be located within convenient reach of the operator. If desired, the heating coil may be connected in series with the starting motor, or it may be connected in multiple therewith and both be controlled by the same switch, as will be apparent to 15 those skilled in the electrical arts.

The lower end of heater pipe 14 is flanged at 47 and secured to the fuel pipe casting 31 making a gas tight joint therewith, by 20 means of the coupling 48 and nipple 49. 50 is any convenient pipe connection for conducting away the exhaust gases or the hot water from the engine jacket either of which may be passed through the heater pipe 14.

30 The upper end of heater pipe 14 is packed against leakage by means of the packing 51, preferably of asbestos, the gland 52, and the nut and pipe connection 53.

To prevent injury to the air intake valve 3 35 in case of back pressure in the intake passages, by reason of back-firing or other causes, I provide the relief valve 12, held normally closed by the spring 54 acting between the valve 12 and the bracket 54^a which 40 is secured to the body casting 1 by the screws 55, 55.

56 is the customary throttle valve controlling the outlet of the mixture of fuel and air from the mixing chamber 4.

45 The centering support 13 consists of a ring cast as a hub to the ribs or spokes 15, 15 which form a stop for the opening of the air inlet valve.

The air inlet valve 3 consists of a series 50 of concentric plates or truncated cones 3^a, 3^b, 3^c, 3^d, each seated upon the next smaller, the smallest one being seated upon the top of the fuel pipe 31 adjacent to the fuel inlet or orifice 57 which is formed at the top of the fuel 55 heating chamber 32 surrounding the heater pipe 14. Each of the plates or cones forming valve 3, has an upward cylindrical extension from its smaller end and a downward cylindrical extension from its larger end. 60 58 is a cylindrical weight on top of valve 3, which is free to slide up and down in chamber 2. This weight may be varied to effect a change in the opening of the valves. The use of gravity only provides a constant resistance to the opening of valve 3, regardless 65

of the distance the valve has opened, and insures a practically constant velocity of the incoming air as it passes the fuel nozzle. When the engine is running slowly, all four of the laminæ 3^a, 3^b, 3^c and 3^d, of valve 3, 70 together with weight 58 will be lifted away from the top of the fuel pipe 31 until the suction caused by the pistons balances the combined weight of the valve 3, and the weight 58, or, the smaller lamina 3^a, strikes 75 the valve stop 15. As the speed of the engine increases, sufficient suction will be produced to lift the three remaining lamina 3^b, 3^c, 3^d, and weight 58 simultaneously away from lamina 3^a, and they will in turn be 80 held in balanced suspension or will rise until lamina 3^b strikes valve stop 15.

In like manner, further increase of engine speed will result in the lifting of laminae 3^c and 3^d, in turn. 85

By proportioning the relative weights and areas of the valvular laminæ 3^a, 3^b, 3^c and 3^d, and the weight of 58, the velocity of the air passing the nozzle orifice and the valve 3 may be varied as desired. For instance, assuming the engine running and the valve 3 open to the extent that lamina 3^a is just striking the valve stop 15, then, if the effective area of the valve made up of laminae 3^b, 3^c and 3^d, be relatively small in proportion to the weight they support, lamina 3^b will not leave its seat until the suction of the pistons, and the velocity of the air through the valve 3 have increased. Other relative variations of areas and weights will 100 be apparent to those skilled in the art. If desired, a constant opening of the inner and smaller lamina 3^a, may be maintained by means of spacers 63, as shown in Fig. 8.

In Fig. 2, the valve 3 is shown at full 105 opening with all the laminæ against stop 15. It will be seen that the air which carries the fuel into the mixing chamber 4 is confined to the relatively small passage between the heater pipe 14, and the cylindrical portion of lamina 3^a, where it will become very hot and intimately mixed before combining with the air entering between the other laminæ. The entire charge of air and fuel will subsequently become thoroughly mixed 115 in mixing chamber 4 and absorb further heat from heater pipe 14 and the walls of the mixing chamber which are in proximity to and are heated by heater pipe 14.

In Figs. 6 and 6^a, I have shown the means 120 I prefer to employ to keep the laminæ central with the heater pipe and with each other. At a number of points *e f g*, &c., in the cylindrical portions, the metal is slit and bent into radial projections so as to 125 bear upon the adjacent laminæ, thus holding them central and in axial alinement.

In Fig. 5, is shown an adjustable fuel inlet, in which the size of the inlet 57^a may be altered as desired. In this construction 130

the end of the fuel pipe 31 is threaded and has screwed upon it the ring 59 and lock nut 60. The end of ring 59 is bored with a conical hole corresponding with the external cone 61, which is secured to heater pipe 14. The size of the inlet 57^a may be changed by adjusting the position of ring 59 and lock nut 60 upon fuel pipe 31.

In Fig. 1 are shown the fuel supply pipe connections which I prefer to use and which will now be described. 90 is a threaded plug or nipple which forms the valve seat for the float valve 26. 91 is a hole bored in 90 for the reception of a strainer or filtering material, such, for instance, as absorbent cotton. 92 is a coupling. 93 is a packing nipple. 94, 94^a and 95 are fittings leading to the fuel supply pipe 96. 97 is a threaded plug forming a guide for the float valve stem. 98, 99 are screws for holding the float cover chamber in place.

It will be understood that while I show two float valves controlled by a single float, I do not limit the scope of my present invention to such construction but may employ a single float valve and fuel supply pipe and any well known form of float and float valve.

I am aware that carbureters having fuel heating chambers and heater pipes extending through them have been previously proposed, but in those with which I am familiar the heater pipe does not pass directly through the fuel inlet or orifice as for instance my heater pipe, 14, passes through my fuel inlet or orifice, 57. This is an important feature of my carburetor as the incoming fuel which is progressively heated by contact with the heater pipe as it passes through the fuel heating chamber continues to receive heat from the heater pipe while passing through the fuel inlet or orifice to the mixing chamber.

By my arrangement of the fuel heating chamber, the heater pipe, and electric heating coil, the entering air and fuel are so heated that they reach the highest temperatures which they attain before entering the mixing chamber, as they are about to pass through the air and fuel inlets and mingle in the mixing chamber.

I therefore particularly point out and distinctly claim as my invention:

1. In a carburetor, a casing provided with a mixing chamber, having an air inlet, a fuel inlet, and a mixture outlet, a heater pipe extending through the mixing chamber, the air inlet and the fuel inlet, and an air inlet valve adjacent to the fuel inlet, adapted to deflect the incoming air across said fuel inlet against said heater pipe.

2. In a carburetor, a mixing chamber, an annular fuel inlet, an annular air inlet, one inlet surrounding the other, a valve for the air inlet, a heating means surrounded by the

inner inlet, and another heating means surrounded by the outer inlet, whereby both the fuel and the air are heated on the way to the mixing chamber.

3. In a carburetor, a casing provided with a mixing chamber having an air inlet and a mixture outlet, a vertical heater pipe extending through the air inlet and the mixing chamber, a fuel pipe surrounding the heater pipe within the air inlet, forming a fuel heating chamber also surrounding the heater pipe, the fuel heating chamber having an annular orifice surrounding the heater pipe and forming a fuel inlet to the mixing chamber, and an annular air inlet valve closing the air inlet and having its seat upon the fuel pipe.

4. In a carburetor, a casing provided with a mixing chamber having an annular fuel inlet, an air inlet surrounding the fuel inlet, and a mixture outlet, and a plurality of successively-opening concentric valves, controlling the admission of air through the air inlet to the mixing chamber.

5. In a carburetor, a casing provided with a mixing chamber having an annular fuel inlet, an air inlet surrounding the fuel inlet, and a mixture outlet, a plurality of successively-opening concentric valves controlling the admission of air through the air inlet to the mixing chamber, and means for closing said valves exerting a pressure on all the valves through the medium of the outer one.

6. In a carburetor, a casing provided with a mixing chamber having an annular fuel inlet, an air inlet surrounding the fuel inlet, and a mixture outlet, a plurality of successively-opening concentric valves controlling the admission of air through the air inlet to the mixing chamber, and means for limiting the opening of said valves holding them all open under suction action.

7. In a carburetor, a casing provided with a mixing chamber having a fuel inlet, an air inlet surrounding the fuel inlet, and a mixture outlet, and a plurality of successively opening concentric valves controlling the admission of air through the air inlet to the mixing chamber, the smallest valve being seated upon the wall of the fuel inlet, and each of the remaining valves being seated upon the next preceding valve.

8. In a carburetor, a casing provided with a mixing chamber having a fuel inlet, an air inlet surrounding the fuel inlet, and a mixture outlet, a heater pipe extending through the mixing chamber, the air inlet and the fuel inlet, and a plurality of concentric valves controlling the admission of air through the air inlet to the mixing chamber.

9. In a carburetor, a casing provided with a mixing chamber having a fuel inlet, an air inlet surrounding the fuel inlet, and a mixture outlet, a heater pipe extending through the mixing chamber, the air inlet and the

fuel inlet, and a valve seated upon the wall of the fuel inlet, controlling the admission of air through the air inlet to the mixing chamber.

5 10. In a carbureter, a casing provided with a mixing chamber having a fuel inlet, an air inlet surrounding the fuel inlet, and a mixture outlet; two concentric, successively-opening, annular valves controlling the admission of air through the air inlet to the mixing chamber, the smaller one of said concentric valves being provided with a tubular extension rising from it and extending into the mixing chamber beyond said fuel inlet; and means for arresting the valves in open position.

11. In a carbureter, a casing provided with a mixing chamber having a fuel inlet and an air inlet surrounding the fuel inlet and also a mixture outlet; a plurality of concentric, successively-opening, annular valves controlling the admission of air through the air inlet to the mixing chamber, each of these valves being provided with a tubular extension rising from it and extending into the mixing chamber beyond said fuel inlet; and means for successively arresting the valves in open position.

12. In a carbureter, a casing provided with a mixing chamber having a fuel inlet and an air inlet surrounding the fuel inlet and also a mixture outlet; a plurality of concentric, successively-opening, annular valves controlling the admission of air through the air inlet to the mixing chamber, each of these valves being provided with a tubular extension rising from it and extending into the mixing chamber beyond said fuel inlet; and means for arresting the valves in succession in open position, the arresting of the innermost valve occurring first, for the purposes herein set forth.

13. In a carbureter, a mixing chamber, an annular fuel inlet and an annular air inlet, one inlet surrounding the other, a plurality of successively-opening concentric valves controlling the admission of air through the

inlet to the mixing chamber, and means for successively arresting the valves all in open position.

50 14. In a carbureter, a casing provided with a mixing chamber having an annular fuel inlet, and an annular air inlet, one inlet surrounding the other, a plurality of successively-opening concentric valves controlling the admission of air through the inlet to the mixing chamber, said valves being overlapped upon each other, and means for successively arresting the valves all in open position.

55 15. In a carbureter, a mixing chamber, an annular fuel inlet, an annular air inlet, one inlet surrounding the other, a valve for the air inlet, a heater for the inner inlet and another heater for the outer inlet, whereby 65 both the fuel and the air will be heated on the way to the mixing chamber.

60 16. In a carbureter, the combination of a mixing chamber, a heater extending therethrough consisting of an exhaust pipe, two 70 concentric inlets around said exhaust pipe at the inlet side of the mixing chamber, the fuel inlet being adjacent the exhaust pipe, another heating device located in the air inlet and surrounding the fuel inlet, whereby 75 both the fuel and the air are heated on the way to the mixing chamber, and a valve for the air inlet located between the exterior heater and the mixing chamber.

75 17. In a carbureter, the combination of a 80 mixing chamber, means forming an air inlet and also a fuel inlet for the mixing chamber, these inlets being arranged one within the other, an exhaust pipe for directly heating the inner inlet, and another heating means 85 for directly heating the outer inlet, and a valve located between the heater for the air inlet and the mixing chamber.

In testimony whereof I have affixed my signature in presence of two witnesses.

FRANK L. SESSIONS.
